UNITED STATES PATENT OFFICE.

JOHN MORESHED, OF BROOKLINE, MASSACHUSETTS.

ANGLE DIVIDERS OR BISECTING BEVELS.

Application filed April 16, 1927. Serial No. 184,243.

My invention relates to improvements in tools of the type known as angle dividers or bisecting bevels used by carpenters, cabinet makers and other tradesmen.

5 It has for its purposes to provide new and novel combinations and improvements in an angle bisecting device adaptable for convenient use in conjunction with the well known and widely employed iron mitre box; 10 to provide an angle bisecting device which, when the center of a given angle has been established by the locating arms, embodies means for locating and holding in fixed position what I choose to term the third bevel 15 blade, while and after the bisecting arms are moved to a closed or other position; to provide a new and novel combination embodying two bisecting arms, and a third bevel blade adaptable for determining the 20 center of any desired angle, and to simplify the procedure in establishing such center; to provide a novel construction providing for the locking of the third or bevel blade in any desired position while the bisecting arms 25 are free to close or position otherwise; and to provide the various other advantages and results made evident from the following specification.

I accomplish the objects of my invention as 30 shown in the accompanying drawings which form a part of this specification and in which Figure 1 shows my assembled device in an open position with its third bevel blade fixed and its bisecting arms in a nearer 35 closed position. Figure 2 shows the third bevel blade fixed and the bisecting arms closed. It is in this position that the device is adaptable for use in iron mitre boxes. Figure 3 shows a side view of my device in 40 its closed position with a sectional view at its hinge end to show the locking device adaptable to control the third bevel blade. Figure 4 shows the detail of the locking nut and threaded bolt on which are hinged 45 the bisecting arms and third bevel blade.

Referring again to Figure 1, A shows the center member slotted at B so as to allow the sliding therein of the threaded screw C, over which is positioned an orifice in one end 50 of each of the locating arms D and E. The nut C² is adaptable to tighten and lock the arms D and E in any desired position. The opposite ends of the locating arms D and E are pivotally hinged by means of orifices in 55 said arms fitted over the pivots H and I on the bisecting arms F and G. The pin J

is projected from the under side of the bisecting arm G, adaptable to engage the third bevel blade K as the bisecting arm G is opened, and position said third bevel blade 60 so as to exactly register with the arm G.

Referring again to Figure 4, L shows the head of threaded bolt on which are hinged the bisecting arms and third bevel blade. M shows that portion of the bolt stem which 65 is flattened to fit a similar shaped orifice in the center post A to avoid turning as the locking nut N is tightened. O shows a shoulder slightly thicker than the combined arms F and G, adaptable to pass through 70 orifices in the said arms, and to allow them free play when the locking nut P is tightened.

Similar letters refer to similar parts throughout the various views. 75

I will now describe the steps required to use my improved device with a mitre box in making a cut of a given angle. Say e. g. if it is desired to fit a moulding into a corner. The hinged end of my device is positioned 80 in the corner and the bisecting arms F and G opened until they contact with the sides which join to make the corner. As the bisecting arm G is opened the projecting pin J similarly opens the third bevel blade K 85 until it also contacts with the side against which the arm G rests. While the blades are in this position the nut N is tightened, locking the third bevel blade K in position. The bisecting arms F and G are then closed 90 and the center post A laid parallel to the side of mitre-box.

The cutting angle of the mitre-box is next 95 adjusted parallel to the third bevel blade and the cut then made. The use of dividers is not required.

While I have illustrated and described a preferred construction for carrying my invention into effect, this is capable of variation or modification without departing from 100 the spirit of the invention. I therefore do not wish to be limited to the exact details of construction herein set forth but desire to avail myself of such variations and modifications as come within the scope of the 105 appended claims.

Having thus described my invention I claim as new and desire to secure by Letters Patent of the United States of America:

1. An instrument of the type described 110 comprising an elongated base member formed with a slot therein, three blades pivotally

mounted at a common point on one end of
said base member, a pair of arms having one
of their ends pivoted to two of the blades
constituting a pair and the remaining ends
5 pivoted to a common means slidable in the
slot in the base so that the said pair of blades
connected to said arms will move outwardly
from the base and inwardly to the base
simultaneously and at the same relative angle
10 with respect to the base, a pin on one of said
pair of blades engaging the remaining blade
to move the same when the pair of blades
are moved outwardly from the base, and
means for holding the said remaining blade
15 in the position to which it has been moved
when the other blades are returned to their
normal closed position.

2. An instrument of the type described
comprising an elongated base member formed
20 with a slot therein, three blades pivotally
mounted at a common point on one end of

said base member, a pair of arms each having
one of their ends pivotally connected to two
of the blades constituting a pair and the
remaining ends pivoted to a common means 25
slidable in the slot in the base so that the
said pair of blades connected to said arms
will move outwardly from the base and in-
wardly to the base simultaneously and at the
same relative angle with respect to the base,
a pin on one of said pair of blades engaging
30 the remaining blade when the pair of blades
are moved outwardly from the base to dis-
pose said remaining blade in a position of
registry with the blade carrying the pin at
35 its outermost position, and means for hold-
ing the said remaining blade in the position
to which it has been moved when the other
blades are returned to their normal closed
position.

In testimony whereof I affix my signature.
JOHN MORESHED.
